RETRACTABLE SIDEWALK TELLER SYSTEM

Clarence D. Ellithorpe, Milford, Conn., assignor
to Duplex Electric Company, Inc., New York,
N. Y., a corporation of Delaware

Application November 21, 1951, Serial No. 257,487

6 Claims. (Cl. 186—1)

1

This invention relates to a teller apparatus for sidewalk banking service or the like and is particularly concerned with an arrangement movable between an operative position projecting above the sidewalk and a retracted position in which the apparatus is below the sidewalk surface.

In prior devices, the sidewalk teller stand has been mounted permanently in a position projecting upwardly from the sidewalk. The stand usually is adjacent the curb, the teller being inside the bank and the customer being at sidewalk level. Previous stands have had means for transferring articles and have had means of communication between the customer and the teller, the teller normally being below street level, although he may be in the stand. Because of the permanent mounting of the previous stands, they may obstruct pedestrian traffic and may be subject to night vandalism.

One of the objects of this invention is to provide a sidewalk teller apparatus in which an enclosed stand extends upwardly from the sidewalk for use in the performance of sidewalk banking services, and which may be retracted to a position such that pedestrian traffic will not be obstructed and the stand will be in a protected position when not in use.

Another object of the invention is to provide an improved teller apparatus which is simple in construction, easy of operation, and wherein all the advantages of a permanently mounted stand are present.

In one aspect of the invention, a teller apparatus is provided wherein the stand or kiosk is movable by any suitable mechanism between a raised or operative position in which it extends upwardly from the sidewalk, and a retracted or storage position in which the entire stand is located beneath the sidewalk in a pit with the top of the stand flush with the sidewalk. The stand can have an upright wall portion with an opening for transferring articles and a window providing visual communication between a teller or service person and a customer.

In a preferred embodiment, a fluid pressure operated motor located in said pit beneath the sidewalk can be employed for raising and lowering the stand through the opening in the sidewalk. A seal can be provided between the margins of the vertical walls of the pit or the sidewalk opening and the stand for sealing the joint therebetween and yet permitting raising and lowering of the stand.

One form of the sealing arrangement of the

2

stand relative to the pit in the sidewalk can include a resilient material suitably carried by the vertical walls of the pit adjacent the sidewalk opening so as to extend inwardly and upwardly from the vertical walls of the pit. The stand can have a member near the top thereof and a member near the bottom thereof, each of these members extending around the periphery of the stand and appropriately cooperating with said resilient material for sealing the joint between the stand and margins of the sidewalk opening or vertical walls of the pit. The upper of said members extends upwardly and outwardly from adjacent the upper end of the stand and is joined at its upper edges to the outer edges of the projecting stand roof. The upper member will engage said resilient material member when the stand is in a lowered or storage position. The other member can extend downwardly and outwardly to engage the resilient member when the stand is in its raised or operative position. Conduits may be provided in the sidewalk to connect the space adjacent to and above the juncture of the resilient member and the walls of the pit so as to conduct away any water and dirt that may collect in said space.

Other objects, features, and advantages of the invention will become apparent from a consideration of the following description and drawing of one illustrative embodiment of the invention. In the drawings:

Fig. 1 is a vertical cross-sectional view of a retractable teller apparatus embodying the invention;

Fig. 2 is a broken front elevational view, partly in section, of an upper portion of the apparatus shown in Fig. 1;

Fig. 3 is an enlarged fragmentary cross-sectional view showing the sealing structure which acts to keep materials from falling into the pit beneath the sidewalk when the stand is in its retracted position;

Fig. 4 is a vertical cross-sectional view showing the front wall of a modification of the teller apparatus embodying the principles of my invention;

Fig. 5 is a vertical cross-sectional view taken generally along the line 5—5 of Fig. 4;

Fig. 6 is a sectional view taken along the line 6—6 of Fig. 4;

Fig. 7 is a rear elevational view of the teller apparatus of Fig. 4.

In the arrangements shown for illustrating the principles of the invention, the teller apparatus includes an enclosed stand or kiosk 10 movable

through opening 12 formed in sidewalk 14 adjacent curb 16 of street 18. The enclosed stand 10 is vertically movable through said sidewalk opening between a raised or operative position in which it extends upwardly above the sidewalk, and a storage or retracted position within pit 22 disposed underneath the sidewalk opening, by a lift mechanism generally indicated at 20, located in the pit 22. Below the curb 16 is a retaining wall 24 which forms a side wall of the pit 22.

The enclosed stand is provided with upright walls including a front wall 26 having an opening 27 for the transfer of articles involved in business transactions in and from the stand by a customer located beside the stand. The upright walls include a rear wall 28, and side walls 30 and 32. A flat roof 34 closes off the upper end of the stand and in addition to preventing the entrance of dirt and water thereinto, also serves the additional purpose of acting as a portion of the sidewalk by closing the sidewalk opening 12 when the stand is in a lowered position in pit 22. The lower end of the stand is supported on a platform 36 secured upon the upper end of lift mechanism 20.

Lift mechanism 20 may be of any conventional construction but preferably has a fluid operated plunger 38 slidably mounted in a cylinder (not shown) in the lower end of the pit. By admitting fluid under pressure to the cylinder, plunger 38 may be made to move upwardly until the stand being carried by it on the platform 36 extends to the proper height above the sidewalk.

Referring more particularly to Figs. 1, 2 and 3, there is shown therein an embodiment of the invention usable when the teller occupies a position in a room or zone, generally indicated at 40, located beneath the sidewalk and of which the pit 22 may form a part. The conveying means for transmitting articles between a position opposite a customer and a position in reach of the teller located in the room beneath the sidewalk may be carried entirely by the stand. In the embodiment disclosed, the stand has been made of a length such that an elevator mechanism may be mounted therein along one wall to convey the articles between customer and teller positions. The necessary access to the elevator mechanism can be through openings suitably located in the walls of the stand and these include the opening 27 formed in the upper portion of the front wall 26 and an opening 41 formed in the lower portion of the rear wall 28.

The elevator mechanism includes a car 42 movable in a shaft 43 fixed to the front wall 26 of the stand. The movements of the elevator can be controlled by a reversible electric motor 44 energizable by a switch 46 mounted adjacent counter 48, said counter extending inwardly into the stand from the lower edges of the lower opening 41. The electric motor 44 is connected to the elevator car 42 by a chain 50, the free ends 50a and 50b being connected respectively to the upper and lower portions of the car. The lower looped portion of the chain 50 passes around a sprocket wheel 52 carried by the driving shaft 54 of the electric motor 44. The chain passes over two other sprocket wheels, one of which, as seen at 56, is mounted directly above the upper position of the car 42, while the other (not shown) is mounted to one side of the car to prevent entanglement of the chain 50 with the car. By suitable actuation of the switch 46, the motor 44 may be made to rotate to move the elevator car between its two delivery positions.

To enable the identification by the teller be-

neath the sidewalk of a prospective customer who is outside of the stand, a system of visual communication is provided. For example, parallel mirrors 58 and 60 are mounted in the stand at half-right angles to the longitudinal axis thereof and are disposed behind windows 62 and 64 formed in opposite wall portions 26 and 28 of the stand respectively. The upper window 62 is located above the opening 27 and at the eye level of the customer. The lower window 64 is formed in the rear wall 28 of the stand above the opening 41 therein and at eye level of a teller stationed in room 40. Mirrors 58 and 60 are arranged to provide a wide range of vision between the two eye levels along the path indicated generally by the lines S in Fig. 1.

Manifestly, however, the upper portion of the stand 10 when projecting above the sidewalk 14 must be kept closed and protected against vandalism and unauthorized entry. For this purpose, wall 26 is provided with a generally tubular member 66 which extends inwardly from the edges of the window 62. A bullet-resistant glass panel 68 is fixed over the inner end of this tubular member in front of the upper mirror 58.

Similar protection is obtained for the opening 27 by providing a door 70 for the opening 27, said door being operated preferably by the teller. Door 70 is pivotally mounted at its lower end at 72, and is adapted to have its upper end swing outward and downward to a position in which it also serves as a tray or counter for the customer. The movements of the door to and from closed position are effected by suitable motor operated mechanism under the control of the teller. The motor apparatus may be of various forms but as diagrammatically illustrated, it includes a motor 74 which rotates a disc 76 eccentrically connected to one end of a connecting rod 78, the other end of which is connected to a lever arm 80 fixed to the door. Suitable switching means for energizing the motor may be provided on the lower part of the stand within easy access of the teller.

The teller apparatus may be provided with a call button 82 (Fig. 2) electrically connected to chimes 84 mounted on the lower portion of the stand. A suitable oral communication system also may be provided which may take the form of a two-way microphone-speaker arrangement under control of the teller. The upper speaker 50 may be adjacent opening 62 so as to provide the necessary sound transmitting means at the customer position. Additional openings 86 and 88 also may be formed in the front wall 26 of the stand at either side of the door closed opening 70 and these may be used to mount a clock and a thermometer respectively.

Thus, a teller apparatus has been embodied into one movable unit which is capable of being used to perform all of the customary teller functions and which can be lowered after business hours to a protected position which will not obstruct pedestrian traffic. In the lowered position of the teller apparatus, however, it is necessary to close the sidewalk opening 12 so as to prevent tripping of pedestrians coming in contact therewith and so as to prevent water entering the pit.

This is accomplished by lowering the stand 28 to a point where the horizontal flat roof 34 is disposed so that its upper surface is flush with the upper surface of the sidewalk 14. The roof 34 extends beyond the juncture of the roof with the side walls of the stand and, as seen in Fig. 3, the terminating edges of the roof lie approximately in the middle of the space formed be-

tween the walls of the stand and the edges of the sidewalk opening 12. In the lowered position of the stand, the roof disposed at the level of the sidewalk cooperates with a frame 90 disposed about the upper outer edge of the sidewalk opening to form a substantially continuous surface substantially closing all entrance into the opening 12 and the pit 22 beneath the sidewalk. Preferably, the roof 34 and the frame 90 are formed with a non-skid top of any well-known construction to prevent slipping of pedestrians walking thereupon. A member 92 is disposed about the periphery of the upper end of the stand 10 and extends upwardly and outwardly from the side walls of the stand to a juncture with the outer edges of the roof 34 to form a toe guard effective to deflect the foot of a person on the sidewalk from beneath the roof of the stand as it is lowered into the storage position in pit 22.

A water-tight seal is effected in the sidewalk opening 12 about the stand 10 in both its operating and storage positions to prevent unwanted flow of dirt and water into the pit. Around vertical walls of the pit 22 adjacent the opening 12, an angle iron 96 can be provided supporting resilient member 94 which extends upwardly and inwardly within the opening 12. Mounted about the periphery of the stand 10 and at the level of the surface of the sidewalk 14 when the stand is in raised position, is a member 98 extending downwardly and outwardly into the space between the stand and the edges of the opening 12. As seen in Figs. 1 and 2, when the stand 10 is in raised position, the resilient member 94 engages the lower inner side of the member 98 in abutting relation so as to form a seal effective to intercept any dirt and water entering the opening 12 from above the sidewalk. The resilient member 94 cooperates with the upwardly and outwardly extending toe guard 92 (Fig. 3) when the stand is in its lower or storage position to intercept the dirt and water passing into the opening 12 through the space existing between the outer edges of the roof 34 and the inner edges of the frame 90. The flexible member 94 is bent downwardly by the upwardly and outwardly extending member 92 so as to bring about a tight relationship therebetween. The flexible member 94 is secured to the angle iron 96 by a plate 98A held in abutting relationship to it by a plurality of fastening means 100 extending through the angle iron and the flexible member.

The interception of dirt and water entering the opening 12 results in the collection thereof in the space adjacent the angle iron 96 supporting the resilient member 94 and the edges of the opening 12, so that conduit means are provided to carry away such intercepted dirt and water. The conduit means may take the form of drain pipes 102 disposed adjacent curb 16 so as to conduct intercepted dirt and water away from the aforementioned space adjacent the angle iron 96 to the street 18. An angle iron 104 may be disposed about the upper portion of the sidewalk edges surrounding the opening 12 so as to provide a suitable base for mounting the angle iron 96, the frame 90 and the drain pipes 102.

Figs. 4, 5, 6 and 7 illustrate an embodiment of the invention in which the vertically movable stand has been modified so that the teller or person servicing the apparatus may occupy a position therein and face a customer when the stand is in its raised or operative position. In such an arrangement, the stand is of the same general outline as the stand 10 in the previously de-

scribed embodiment, and is provided with a similar window and door closed article transfer opening. The stand differs from the earlier embodiment principally in the omission of the conveying means for the transmission of the articles involved in the transaction between the customer level and the level of the teller. The visual communication means also can be omitted. A floor 110 is provided to support the teller in the stand 10 and a door 112 located in the rear wall 28 of the stand to give access to the stand. It will be observed that the stand in the modified embodiment may be of shorter length, which length is limited only by the height of the teller, it not being necessary to provide a lower opening and window for a teller in a room beneath the sidewalk. In one aspect of the invention, the stand may be entered from the room below the sidewalk through door 112. In another aspect, it is not necessary to provide a room beneath the sidewalk because the stand can be entered through the door when the stand is in its upper position above the sidewalk. In this latter instance, the pit 22 beneath the sidewalk need be of a dimension sufficient to accommodate only the lift mechanism 20 and the stand. In this last arrangement, the money and articles must be transported across the sidewalk from the stand to the bank.

The modified stand also is provided with a counter 114 having the usual instrumentalities for enabling the transfer of articles involved in business transactions, and these may include a cash drawer 116, an article drawer 118, and a pistol pocket 120. The counter is supported by the front wall 26 and by legs 121 so that the upper surface thereof is adjacent the bottom of the article transfer opening 27.

Door 112 is hingedly secured to the rear wall 28 of the stand, the door carrying a suitable lock construction whereby the teller may prevent unauthorized opening. Door 112 is provided also with a plurality of louvers 122 opening downwardly on the outside which cooperate with a plurality of louvers 124 formed around the upper end of the stand to bring about a circulation of air in the stand sufficient to sustain a service person.

The walls of the stand utilized in the embodiment of Figs. 4 to 7 are preferably formed of materials which protect a teller stationed therein from heat and from injury. In the embodiment shown, these desired qualities have been obtained by forming the walls and roof of the stand 55 of spaced steel plates having an insulating material, such as glass fiber insulation, disposed therebetween. A wood panel ceiling 126 is mounted in the stand a distance beneath the roof so as to obtain an air space providing additional heat protection for the teller person. The ceiling may be recessed as at 128 to accommodate a pair of fluorescent light tubes 130. The ceiling also is provided with an opening 132 having a louver 134 and constituting a passageway through which air entering the lower louvers 122 may reach the louvers 124 disposed above ceiling 126.

The rear wall 28 and interconnecting walls 30 and 32 may be provided with windows 136, 138 and 140, respectively, covered with transparent bullet-resistant glass to enable the teller to see around the stand in all directions. As space is at a premium in an arrangement of this type, the windows are set flush with the side walls of the stand and the glass panel for the front window 62

is not recessed as in the embodiment of Figs. 1 to 3.

It will be understood that the embodiments described above and illustrated in the accompanying drawings are exemplary only and that various changes and omissions may be made without departing from the spirit of the invention as defined by the following claims.

What is claimed is:

1. In a teller apparatus movable between a raised operative position relative to a sidewalk and a lowered position flush with said sidewalk, said sidewalk having an opening therein with a storage pit therebeneath, the combination including a closed stand movable through said sidewalk opening to an elevated position in which the upper portion of the stand is above the level of the sidewalk and the lower portion is opposite an attendant's station underneath the sidewalk, said upper portion having an aperture therein for the transfer of articles into and out of the stand, an article carrying means movable in said stand between a position behind said aperture and a position in the lower portion of the stand opposite the attendant's station when the stand is in elevated position, and means for moving said stand through said sidewalk opening between said elevated position and a retracted position in the pit beneath the sidewalk.

2. In a teller apparatus movable between a raised operative position relative to a sidewalk and a lowered position flush with said sidewalk, said sidewalk having an opening therein with a storage pit therebeneath, the combination including a closed stand movable through said sidewalk opening to an elevated position in which the upper portion of the stand is above the level of the sidewalk and the lower portion is opposite an attendant's station underneath the sidewalk, said upper portion having an aperture for the transfer of articles into and out of the stand, an article carrying means movable in said stand between a position behind said aperture and a position in the lower portion of the stand opposite the attendant's station when the stand is in elevated position, a window formed in the upper portion of the stand above said aperture therein, a window formed in the lower portion of said stand, a pair of cooperating parallel mirrors disposed in said stand behind said windows enabling visual communication between a customer above the sidewalk and an attendant at said station below the sidewalk, a plunger vertically movable in said pit and supporting at its upper end the stand from beneath, and means for operating said plunger to move the stand through said sidewalk opening between an elevated position in which said stand extends upwardly from the sidewalk and a retracted position in said pit beneath the level of said sidewalk and flush therewith.

3. In a teller apparatus movable between a raised operative position relative to a sidewalk and a lowered position flush with said sidewalk, said sidewalk having an opening therein with a storage pit therebeneath, the combination including a closed stand adapted to extend upward from said sidewalk opening in a raised position and having a vertical wall portion with an aperture for the transfer of articles into and from said stand, an upwardly and outwardly extending upper member adjacent the upper end of said stand and extending around the periphery thereof, said member extending toward the margins of said sidewalk opening when the stand is in a lowered position, a downwardly and outwardly

extending lower member around the periphery of said stand at approximately the level of the sidewalk when the stand is in a raised position, and a strip of resilient material extendable between 5 margins of said sidewalk opening and the appropriate one of said upper and lower members when it is opposite thereto so as to seal the space between the stand and the margin of said sidewalk opening when the stand is in raised or lowered position.

4. In a teller apparatus movable between a raised operative position relative to a sidewalk and a lowered position flush with said sidewalk, said sidewalk having an opening therein with a storage pit therebeneath, the combination including a closed stand adapted to extend upward from said sidewalk opening in a raised position and having a vertical wall portion with an aperture for the transfer of articles into and from said stand, an upwardly and outwardly extending upper member adjacent the upper end of said stand and extending around the periphery thereof, said member extending toward the margins of said sidewalk opening when the stand is in a lowered position, a downwardly and outwardly extending lower member around the periphery of said stand at approximately the level of the sidewalk when the stand is in a raised position, and a strip of resilient material carried by the walls of said pit adjacent the margins of said sidewalk opening, said resilient material cooperating with said upper member when the stand is in lowered position to effect a seal and cooperating with said lower member when the stand is in raised position to effect a seal.

5. In a teller apparatus movable between a raised operative position relative to a sidewalk and a lowered position flush with said sidewalk, said sidewalk having an opening therein with a storage pit therebeneath, the combination including a closed stand adapted to extend upward from said sidewalk opening in a raised position and having a vertical wall portion with an aperture for the transfer of articles into and from said stand, an upwardly and outwardly extending upper member adjacent the upper end of said stand and extending around the periphery thereof, said member extending toward the margins of said sidewalk opening when the stand is in a lowered position, a downwardly and outwardly extending lower member around the periphery of said stand at approximately the level of the sidewalk when the stand is in a raised position, and a strip of resilient material carried by the walls of said pit adjacent the margins of said sidewalk opening, said resilient material cooperating with said upper member when the stand is in lowered position to effect a seal and cooperating with said lower member when the stand is in raised position to effect a seal, and conduit means connected to the space above said resilient strip for draining water therefrom.

6. In a teller apparatus movable between a raised operative position relative to a sidewalk and a lowered position flush with said sidewalk, said sidewalk having an opening therein with a storage pit therebeneath, the combination including a closed stand adapted to extend upward from said sidewalk opening in a raised position and having vertical wall portions with a flat roof extending beyond said wall portions, said flat roof forming a portion of the sidewalk surface when the stand is in a lowered position, an aperture for the transfer of articles into and from said stand, an upwardly and outwardly extending upper

member adjacent the upper end of said stand and extending around the periphery thereof, said upper member joining the edges of said flat roof, said member extending toward the margins of said sidewalk opening when the stand is in a 5 lowered position, a downwardly and outwardly extending lower member around the periphery of said stand at approximately the level of the sidewalk when the stand is in a raised position, and a strip of resilient material extendable between 10 margins of said sidewalk opening and the appropriate one of said upper and lower members when it is opposite thereto so as to seal the space between the stand and the margin of said sidewalk

opening when the stand is in raised or lowered position.
